(57) **CLAIM**

The ornamental design for a pedal scooter, as shown and described.

DESCRIPTION

FIG. 1 is a perspective view of an embodiment of the design for a pedal scooter;

FIG. 2 is a lateral/side elevation view of the embodiment of the design of FIG. 1;

FIG. 3 is lateral/side elevation view of the embodiment of the design of FIG. 1 on the opposite side of the side depicted in FIG. 2;

FIG. 4 is a front elevation view of the embodiment of the design of FIG. 1;

FIG. 5 is a rear elevation view of the embodiment of the design of FIG. 1;

FIG. 6 is a top plan view of the embodiment of the design of FIG. 1;

FIG. 7 is a bottom plan view of the embodiment of the design of FIG. 1;

FIG. 8 is a perspective view of a further embodiment of the design for a scooter;

FIG. 9 is a lateral/side elevation view of the embodiment of the design of FIG. 8;

FIG. 10 is lateral/side elevation view of the embodiment of the design of FIG. 8 on the opposite side of the side depicted in FIG. 9;

FIG. 11 is a front elevation view of the embodiment of the design of FIG. 8;

FIG. 12 is a rear elevation view of the embodiment of the design of FIG. 8;

FIG. 13 is a top plan view of the embodiment of the design of FIG. 8; and,

FIG. 14 is a bottom plan view of the embodiment of the design of FIG. 8.

Any components or portions in the accompanying drawings shown in broken lines form no part of the claimed design or a specified embodiment thereof.

1 Claim, 10 Drawing Sheets
